(57) **CLAIM**

The ornamental design for a deadbolt, as shown and described.

DESCRIPTION

FIG. 1 is a perspective view of the new design for a deadbolt;

FIG. 2 is a front elevational view of the new design for a deadbolt; and,

FIG. 3 is a right side elevational view of the new design for a deadbolt.

The broken lines are for illustrative purposes only and form no part of the claimed design.
